[57] **ABSTRACT**

[21] Appl. No.: 95,245

A method and equipment for controlling the temperature of heated gas forced through a plurality of ducts from a heating chamber, in which each duct has an associated variable flap which sets the cross section of the duct and a temperature sensing device which retains the flaps in position such that a desired predetermined temperature of the gas forced through the ducts will be maintained.

**METHOD AND EQUIPMENT FOR HEATING GAS
AND MAINTAINING A DESIRED TEMPERATURE
IN A PLURALITY OF FEED DUCTS**

The invention concerns a method and equipment for the central heating of a gaseous treatment medium and includes a heating chamber designed for carrying out the method, with a burner controlled by an adjusting motor.

The central heating of a gaseous medium is used not only in heating buildings, but is also of importance in heat drying and heat treatment machines.

Machines for hot-fixing webs of plastic are known, for example, where air circulated by a fan is blown through the web and conducted during its return to the fan through a heating chamber in which the air is heated centrally by an open burning oil or gas flame.

Since the amount of air circulated per unit of time is very great in these machines, the flow cross section which is manually limited in order to guide the air through the heating chamber, forms a considerable throttle resistance in the heating chamber, which can only be overcome by a high driving power of the circulating fan. This power consumption is further increased by the fact that the air is conducted over several baffle plates to achieve a thorough mixing of the portion heated by the flame and passing laterally thereof.

A machine for treating webs has already been suggested where only a fraction of the treatment medium or air to be circulated is sucked in by suction fans through heating chambers, to be heated by burner flames and then fed into a pressure chamber from which the heated portion is fed through branch ducts to the individual treatment medium conduits to be circulated by associated fans.

By heating only a portion of the entire circulated treatment medium, small flow cross sections may be provided in which a close contact of the treatment medium with the burner flames is insured, suffice to adequately limit the throttling losses in the heating chambers.

Frequently it is necessary for heat treatment gases of different temperatures to be provided at different times spread over the duration of a treatment. It may also be necessary to provide heat treatment gas of different temperature simultaneously, from different ducts. In both cases it is necessary to influence the amount of energy to be released for heating.

The solution of this problem, which is not found in the prior art, is the object of the present invention.

For the central heating of a gaseous treatment medium, which is subdivided after heating into individual currents and, after a secondary gas is added, is fed to consumers, the invention suggests for the solution of the problem, to proceed, before the secondary gas is added, to regulate the temperature so that the individual currents undergo individual throttling based on their temperatures after the addition of the secondary gas, the total amount of throttling influencing the amount of energy to be released for heating.

The method according to the invention has not only the advantage of maintaining the central heating of a treatment medium subdivided into individual currents, but it also permits individual temperature regulation of the individual currents, and hence influences the amount of energy to be released by the burner.

For carrying out this method, the invention starts with a heating chamber which has ducts leading off individual currents and a burner controlled by an adjusting motor, and it includes throttle flaps arranged in the ducts which are controlled by adjusting motors, to which are also connected series-connected potentiometers, and furthermore, connections exist to the adjusting motors from resistance thermometers arranged in the ducts which send signals to temperature adjusting regulators and regulators for the flap adjusting motors are connected into the potentiometer circuit.

An embodiment of the heating chamber according to the invention is represented schematically in the drawing in a longitudinal section and will be described more fully below.

Referring now to the drawing, the heating chamber 1 mounts on its end face 2 a gas burner 3 which receives combustion air through line 4, heating gas through line 5 and treating gas through ports 5'. Burner 3 is connected to an adjusting motor 6 controlled by a regulator 7.

A plurality of ducts 8 extend from heating chamber 1 and a secondary air duct 9 leads into each of the ducts 8. A resistance thermometer 11 is positioned in each duct 8 in the path of the flow caused by a fan 10. Throttle flaps 12 controlled by adjusting motors 14 which also control potentiometers 13 determine the cross section of the ducts 8 and hence the flow therethrough.

Temperature regulators 15 are connected by leads 16 to the resistance thermometers 11 and by leads 17 to the adjusting motors 14. The potentiometers 13, which are connected in series, are connected by leads 18 with regulator 7 of adjusting motor 6.

The method of operation of the heating chamber, according to the invention, is as follows.

If it is desired to increase the temperature of the heating medium fed through one or more of the ducts 8, the associated temperature regulator 15 is set to the required temperature. As a result, motor 14 adjusts flaps 12 and also adjusts potentiometer 13. The setting of potentiometer 13 will, through regulator 7 and motor 6, increase the gas flow to burner 3 to increase the temperature.

When the temperature in an associated duct has increased to the desired value, the thermometer will sense the temperature and send a signal to the regulator 15 to again adjust the flaps so that the temperature in each duct can be maintained as desired.

Having thus described my invention, what I claim as new and desire to secure by Letters Patent of the United States is as follows:

1. A heating chamber having a plurality of outlet ducts each providing a separate heated air path, a suction fan in each duct, a gas burner for said chamber, an adjusting motor controlling said burner to vary the gas supplied thereto to vary the heat energy provided thereby, a throttle flap provided for each of said ducts to control the flow of heated gas through the associated duct, an adjusting motor controlling each of said throttle flaps, a potentiometer controlled by each of said flap adjusting motors, a temperature regulator associated with each of said flap adjusting motors, to set the associated flap to a desired position, a thermometer in each of said ducts to sense the temperature of the gas

flowing therethrough, means to supply a secondary gas to each of said ducts between the throttle flap and the thermometer, means connecting each of said thermometers to an associated flap regulating regulator to vary the setting of the associated flap depending upon the temperature sensed, a regulator for said gas burner adjusting motor, and means electrically connecting said potentiometers in series with said burner regulator to vary the heat energy provided thereby based on the setting of said potentiometers.

2. A method for the central heating of a gaseous treatment medium flowing into a heating chamber hav-

ing an associated gas fed burner and having a plurality of individual outlet ducts each having a throttle flap to control the flow of heated gas therethrough, comprising the steps of adding a secondary gas to each of the individual ducts between the throttling flap and the outlet of the duct, sensing the temperature of the combined gaseous treatment medium and secondary gas and based on such temperature simultaneously varying the setting of the throttling flap and the gas flow to the chamber to determine the amount of heating energy provided in the heating chamber.
